UNITED STATES PATENT OFFICE.

OLIVER J. DAY, OF EDGELEY, NORTH DAKOTA.

BLACKBOARD-ERASER.

1,183,801.

Specification of Letters Patent. Patented May 16, 1916.

Application filed February 13, 1913. Serial No. 748,227.

To all whom it may concern:

Be it known that I, OLIVER J. DAY, a citizen of the United States, residing at Edgeley, in the county of Lamoure and State of North Dakota, have invented certain new and useful Improvements in Blackboard-Erasers, of which the following is a specification.

This invention relates to blackboard 10 erasers, and has for its object to simplify the construction of devices of this character, and render same practically dustless, and at the same time provide means whereby the parts may be removed and duplicated, 15 thereby enhancing its value as to durability, economy and cleanliness.

The above and additional objects are accomplished by such means as are illustrated in their preferred embodiment in 20 the accompanying drawings, described in the following specification, and then more particularly pointed out in the claims which are appended hereto and form a part of this application.

25 In describing my invention in detail reference will be had to the accompanying drawings wherein like characters denote like or corresponding parts throughout the several views, and in which:—

30 Figure 1 is a perspective view of an eraser constructed in accordance with my invention. Fig. 2 is a side elevation, the frame casing being shown in section, and Fig. 3 is a section on line 3—3 of Fig. 2.

35 Before proceeding with the description of the drawings I desire to call particular attention to the fact that while I have evolved my invention with particular reference to its application in connection with 40 the cleaning of blackboards, the same may be readily utilized for the purpose of cleaning slates and other similar articles or devices.

45 Referring now to the drawings, the numeral 1 designates the outer casing or frame of the eraser, substantially rectangular in shape and provided with an open face for the purpose of receiving the erasing pads employed in connection with the invention.

50 The said casing is preferably covered with any soft material such as is shown at 2 in the drawings, the same being glued, stitched or otherwise secured upon the exterior of the casing. Disposed within the said casing, 55 when the device is properly assembled, and retained therein by reason of its frictional

engagement with the inner wall thereof, I provide a frame 3 of substantially the same size and shape as the said casing, the said frame having a flange 4 formed integrally therewith and projecting outwardly from the upper edge thereof. In fitting the frame within the casing the edges of the latter are arranged to fit beneath the said flanges thereby maintaining the frame in proper 60 place within the casing. Mounted within the frame and held therein by frictional engagement I provide a plurality of uniformly spaced parallel bars 5, each of which is covered with a strip 6 of any soft downy 65 material, the free ends of each strip projecting beyond the edge of the frame as at 7 so as to form an erasing pad or the contacting surface of the device. Any suitable means such as the staples or pins shown at 8 75 may be employed for fastening the strips in proper place upon the bars 5.

A comparatively large flat strip of material 9 is interposed between the inner face of the casing 1 and the ends of the strips 6, 80 which strips are rendered by the application of oil or other suitable liquid thereupon, capable of impregnating the erasing surface 7 of the strips and rendering the same capable of performing the required function to 85 better advantage, as well as eliminating the accumulation of dust to a marked degree.

90 From the above description, taken in connection with the accompanying drawings it will be seen that the erasing pads or strips may be freely removed for cleaning the same or for the purpose of applying liquid to the pad or strip 9; that by reason of the tight or frictional engagement between the said strips and the inner wall of the frame, the former are held in proper place therein; and that by application of liquid to the strip 9, the same will impregnate the erasing pads or strips 6 by reason of their engagement or contact therewith.

95 Although the strip 9 is shown and described as forming a part of my invention, the same may be readily omitted, and the device used for the purpose for which it is designed; however, the provision of the said strip will materially increase the efficiency and cleaning power of the eraser to a marked degree.

100 It will be understood that the above description and the accompanying drawings comprehend only the general and preferred embodiment of my invention, and that vari-

ous minor changes in the details of construction, proportion and arrangement of parts may be made within the scope of the appended claims and without sacrificing any 5 of the advantages of my invention.

Having thus fully described my invention, what I claim as new and desire to secure by Letters Patent, is:—

1. In an eraser, a holder, a strip of absorbent material held within the said holder, a plurality of uniformly spaced bars disposed within the said holder, erasing strips arranged to embrace the said bars and to project exteriorly of the holder, the said strips being disposed in engagement with the absorbent material, the said bars and the said strips being maintained within the holder by reason of their frictional engagement therewith, as and for the purpose set 20 forth.

2. An eraser including an inner and an

outer telescoping holder, a strip of absorbent material disposed within the said inner holder, flanges formed upon the said inner holder adapted to overlap the edges of the 25 said outer holder, a plurality of uniformly spaced parallel bars disposed within the said inner holder, erasing strips arranged to embrace the said bars, the said strips adapted to extend beyond the edge of the said inner holder, the said strips and the said bars being maintained within the said inner holder by reason of their frictional engagement therewith, and means for fastening the said strips to the said bars, as for the purpose set 30 forth.

In testimony whereof I affix my signature in presence of two witnesses.

OLIVER J. DAY.
